DESIGN FOR A COFFEE MILL

Harold Van Doren, Toledo, Ohio, assignor to The Enterprise Manufacturing Company, of Pennsylvania, Philadelphia, Pa., a corporation of Pennsylvania

Application June 18, 1938, Serial No. 77,916

Term of patent 7 years

To all whom it may concern:

Be it known that I, Harold Van Doren, a citizen of the United States, residing at Toledo, Lucas County, Ohio, have invented a new, original, and ornamental Design for a Coffee Mill, of which the following is a specification, reference being had to the accompanying drawing, forming a part thereof, in which

Fig. 1 is a front elevation of a coffee mill showing my new design; and

Fig. 2 is a rear perspective view thereof.

I claim:—

The ornamental design for a coffee mill, substantially as shown.

HAROLD VAN DOREN.
